DESIGN FOR A COMB OR SIMILAR ARTICLE

Isadore O. Witte, Los Angeles, Calif., assignor to Le Vant Brush Company, Los Angeles, Calif.,
a corporation of California

Application December 16, 1946, Serial No. 135,546

Term of patent 3½ years

(Cl. D86—8)

To all whom it may concern:

Be it known that I, Isadore O. Witte, a citizen of the United States, residing in Los Angeles, in the county of Los Angeles and State of California, have invented a new, original, and ornamental Design for a Comb or Similar Article, of which the following is a specification, reference being had to the accompanying drawing, forming part thereof.

Fig. 1 is a side elevational view of a comb or similar article, showing my new design.

Fig. 2 is an end elevational view, as seen from the left of Fig. 1, omitting surface ornamentation.

Fig. 3 is an enlarged cross-sectional view, as taken on line 3—3 of Fig. 1.

The dominant features of the design reside in the portions shown in full lines. The opposite side of the article is similar to that shown.

I claim:

The ornamental design for a comb or similar article, substantially as shown and described.

ISADORE O. WITTE.
